UNITED STATES PATENT OFFICE.

EDWARD D. CONKLIN, OF NEWARK, NEW JERSEY, ASSIGNOR TO THE WHITEHEAD & HOAG COMPANY, OF NEWARK, NEW JERSEY, A CORPORATION OF NEW JERSEY.

BOTTLE-STOPPER.

SPECIFICATION forming part of Letters Patent No. 767,632, dated August 16, 1904.

Application filed November 2, 1903. Serial No. 179,562. (No model.)

To all whom it may concern:

Be it known that I, EDWARD D. CONKLIN, of Newark, in the county of Essex, in the State of New Jersey, have invented new and useful Improvements in Bottle-Stoppers, of which the following, taken in connection with the accompanying drawings, is a full, clear, and exact description.

This invention relates to improvements in bottle-stoppers, and refers more particularly to cork stoppers and caps or tops therefor. These corks are usually tapering and are of course susceptible to more or less compression or indentation without liability of mutilation, while the portions not compressed remain in their normal expanded condition.

The object is to provide the cork with a cap or top of different material which is easily and permanently secured in position and not only serves as a convenient means for inserting and removing the cork into and from the bottle, but also affords a means for receiving advertising or other printed matter or ornamentation and gives a neat and characteristic appearance to the cork with but slight addition to its cost.

Other objects will appear in the following description.

In the drawings, Figure 1 is an elevation of a cork provided with one form of my improved cap or top. Fig. 2 is an enlarged elevation of the upper end of the cork, showing the cap in section. Figs. 3 and 4 are perspective views showing, respectively, the detached cap complete and the detached upper section or head of the cap. Figs. 5 and 6 are elevations of corks, showing modified forms of caps in section.

Similar reference characters indicate corresponding parts in all the views.

The general form of the cap is that of an inverted cup having its open end reduced in diameter to less size than the diameter of the head of the cork, so that when the cap is placed over and upon the cork the two parts are permanently locked together.

In the preferable form of cap (seen in Figs. 1, 2, and 3) a circular band 1, of sheet metal, is

formed with a central opening 2, and its inner and outer edges are then bent by stamping or pressing in opposite directions to form an inner downturned flange 3, and an outer upturned flange 4, while the intervening portion 5 of the plate lies in a substantially horizontal plane. This constitutes a circular band 55 which is placed over and upon and encircles the large end of the cork, as 6, so that the flange 3 engages the periphery of the cork some distance beneath its upper end face, while the upper edge of the flange 4 lies substantially in the same plane as said upper end face of the cork. The lower flange 3 is of less diameter than the upper end of the cork, which is compressed to receive the same, and after the cap is placed in position the lower 65 edges of the flange 3 are still further compressed inwardly, and thus form an annular groove 7 in the cork, in which the flange 3 is embedded. This groove is therefore some distance beneath the upper end face of the 70 cork, and the upper portion of the cork is free to and does expand to its normal size and overhangs the horizontal portion 5 to prevent withdrawal of the cap. This band may be formed as described either before or after 75 being placed upon the cork, but is brought to nearly the required form before, and in forming the inner flange 3 its inner edge is usually split or broken slightly in radial lines, which forms a series of spurs, and these 80 latter are readily embedded by compression into the cork to interlock the cap with the cork. It now appears that the upper portion of the band is of greater diameter than the lower end which engages the cork and is also 85 of greater diameter than the upper end of the cork, and therefore forms an annular space 8 between the upper end of the cork and band to insure the full expansion of the upper end of the cork after it is compressed to receive 90 the cap. This upper flange 4 flares slightly upwardly and outwardly and receives a cover-section 9, which in this instance consists of a sheet-metal disk 10 and a celluloid disk 11, having their marginal edges interlocked with 95 each other and with the flange 4. The disk

10 covers the upper end of the cork and its encircling band and rests upon the upper edge of the flange 4, while its edge 12 is bent or flanged downwardly and inwardly around 5 the flange 4, and the edge of the disk 11 is also turned or flanged downwardly at 13 around the flange 12 and then upwardly at 14 and is impinged between said flange 12 and the flange 4. It is thus apparent that the disks 10 and 10 11 are locked to the band 1 by reason of the fact that the upper edge of the band is of greater diameter than that of the inner upturned edge of the disk 11.

The cap seen in Fig. 5 is substantially the 15 same as that seen in Figs. 1, 2, and 3, except that the spurs on the inner downturned flange 3 are slightly longer and turn outwardly at the bottom.

In Fig. 6 the cap consists of an inverted- 20 cup-shape shell 15, of wood or other material, having an opening 16 of substantially the same size and shape as the head of the cork, upon which it is fitted and cemented, if desired. Surmounting this shell are metal 25 plates 17, one of which is flanged downwardly at 18 over the upper edge of the shell, and portions of the center of the other are cut to form tongues 19, which are passed downwardly through apertures in the shell and 30 laterally between the shell and cork, so as to lock the metal disk to the wood shell. The upper face of this shell is covered with a celluloid or similar disk 20, having its marginal edges overturned at 21 around the flange 18 35 and impinged between said flange and sides of the shell, whereby both disks are locked to the shell. This celluloid covering in each in-

stance gives a neat and finished appearance to the cork and cap and affords a suitable surface for receiving advertising or other printed 40 matter or ornamentation.

Having thus described my invention, what I claim, and desire to secure by Letters Patent, is—

1. A cap for cork bottle-stoppers, said cap 45 comprising a plate having a central opening, the inner edge being turned downwardly and its outer edge turned upwardly to form oppositely-projecting inner and outer flanges, and a covering interlocked with the upturned 50 flanges.

2. In combination with a cork, a band encircling the head of the cork and having portions of its sides compressed to compress and interlock with the cork, the upper end of the 55 band flaring outwardly and upwardly, and a disk covering the upper end of the cork and having its marginal edges turned downwardly around the flaring portion of the band.

3. In combination with a cork, a metal band 60 having portions thereof compressed around the cork beneath its upper end face, a disk covering the end of the cork and having its marginal edge interlocked with the band, and a second disk of different material covering 65 the former disk and having its edges impinged between the band and said former disk.

In witness whereof I have hereunto set my hand this 19th day of October, 1903.

EDWARD D. CONKLIN.
